DIFFERENTIAL PRESSURE BAILER

William J. Flury, Long Beach, Calif., assignor, by direct and mesne assignments, of one-sixth to Frank Halfen and one-sixth to Louis P. Brandel, both of Long Beach, Calif., and one-half to Paul Cavins, Long Beach, Calif.

Application August 26, 1935, Serial No. 37,794

8 Claims. (Cl. 166—19)

This invention has to do in a general way with oil well operations and is more particularly related to improvements in bailers of the so-called "suction" or more accurately the "differential pressure" type. As is well known to those familiar with the art, bailers of the general class above referred to are extensively used for the purpose of removing sand and other debris from the bottom of oil wells and embody a sand chamber and an air chamber separated by a valve mechanism adapted to be forcefully opened against an excessive pressure in the sand chamber when the unit engages the bottom of the well.

It is one object of this invention to provide in a bailer of the class described, an improved valve mechanism which is opened immediately as the unit is collapsed but which is closed as soon as the unit is extended and remains closed as long as the unit is in extended position. In an arrangement of this character even though the assembly may inadvertently be lowered into the well at a velocity great enough to momentarily collapse the unit when it strikes the liquid in the well, it immediately extends and closes the valve so that the only effect will be to slightly increase the pressure in the air chamber above atmospheric. Even with the slight increase of pressure in the air chamber, which might be effected through this action, the difference between the pressure in the air chamber and the pressure at the bottom of the well is so great that it does not in any way impair the operation of the unit when it reaches the bottom of the hole.

It is another object of this invention to provide improved sealing means between the two telescoping members which operates independently of any packing means to positively seal the air chamber from the liquid in the well whenever the unit is in a freely suspended position.

Still another object of this invention is to eliminate the difficulties ordinarily encountered in dumping or discharging the bails by providing an auxiliary downwardly opening by-pass valve within the bails unit between the air chamber and sand chamber so that when the discharge valve is opened and the pressure in the air chamber is consequently greater than the pressure in the sand chamber, this by-pass valve will be automatically opened to apply pressure from the air chamber to the contents of the sand chamber and effect their discharge. In this way I provide a unit which can be unloaded independently of any movement between the two members. In other words, the unit contemplated by this invention may be unloaded while it is suspended from

the line or cable or it may be unloaded when it is in a substantially horizontal position.

The details in the construction of a preferred form of my invention, together with other objects attending its production, will be best understood from the following description of the accompanying drawing, which is chosen for illustrative purposes only and in which

Fig. 1 is an elevational view partially broken away showing a preferred embodiment of my invention;

Fig. 2 is a fragmentary sectional elevation taken through the valved portion of the unit in a plane represented by the line 2—2 of Fig. 1;

Fig. 3 is a fragmentary sectional elevation similar to Fig. 2 showing the position of the parts when the two telescoping elements are collapsed; and

Fig. 4 is a plan section taken along the line 4—4 of Fig. 2.

More particularly describing the invention as herein illustrated, reference numeral 11 indicates a bails which is formed of two telescoping tubular units indicated generally by reference numerals 12 and 13. The upper unit 12 is provided with a cover cap 15 of conventional type, such cap being provided with a ring or link member 16 to which a suspending cable 17 may be attached. The bottom of the lower member 13 is provided with the conventional inlet and discharge shoe 18 generally indicated by reference numeral 18 which is shown as being provided with a bull nose 19 and has an inwardly opening check valve of the flapper type 20 mounted therein. The discharge valve on this shoe may be of any conventional type and is shown as comprising a sleeve 21 which has ports 22 therein, such ports being adapted for alignment with ports 23 in the wall of the shoe when the sleeve 22 is rotated.

The bottom of the upper member 12 is provided with a bushing or fitting 27 which has a reduced hollow stem 28 on its lower end, such stem slidably extending down through a stuffing box 29 which is mounted in a top bushing 30 on the upper end of the lower member 13. In this way it will be seen that in this form of my invention the upper member 12 becomes what may be termed the inner member of a telescoping unit which includes the bottom member 13 as the outer member.

In the upper end of the lower or outer member 13 I provide an inwardly extending annular shoulder 31 which is shown as being formed on the bottom of the bushing 30. This shoulder is formed so as to provide a seating surface which

is adapted to have sealing engagement with a correspondingly ground or formed surface 32 on the upper edge of a second shoulder which is provided on the bottom of the inner or upper member 13. In this form of my invention the shoulder 32 is shown as comprising the upper edge of a ring member 33 which is locked in place by a cage 33', both the ring and the cage being secured in threaded engagement with the hollow stem 28. This cage member 33' may take various shapes and is shown as comprising downwardly extending legs 34 and 34'. The essential feature of the cage is that it be provided with a port or ports so as to establish communication between the interior of the member 28 and its associated upper member 12 and the interior of the outer or lower member 13.

The bottom of the cage 33' is shown as being formed with or rigidly connected to a downwardly extending valve stem 36 which in turn supports a valve member 37 at its lower end. The valve member 37 has an accurately ground face 38 formed on its upper edge which is adapted to engage with an inwardly extending shoulder 39 provided on the lower or outer member below the region occupied by the port which in this form of my invention is contained within the cage 33'. In this form of my invention the valve seat or shoulder 39 is shown as comprising the lower edge of a bushing member 41 to which the main body tube of the sand chamber or bottom member 13 is connected.

From the construction as described so far, it will be seen that the valve member 37 when it is closed, divides the assembly into what may be termed a sand chamber in the lower portion of the member 13 and an air chamber which includes a portion of the member 13 above the seat 39 and the member 12. In this connection it is an important feature of this invention that the distance between the upper shoulder 38 on the valve member and the shoulder 32 be such that both of these members are engaged by the corresponding shoulders 39 and 31 on the lower or outer member 13 when the unit is in extended position. In this way it will be seen that whenever the bailer is in suspended position the shoulders 38 and 39 constitute a seal between the air chamber and the sand chamber and the shoulders 31 and 32 constitute a positive pressure seal between the air chamber and the outer end portion of the passage in the outer or bottom member 13, which, when the bailer is in use serves to positively seal the air chamber from the liquid in the well irrespective of the packing 29 or any leakage which may have developed therein.

In assembling the units to obtain this positive sealing effect the hollow stem 28 is first inserted into the lower member through the packing box 29 after which the ring member is screwed on the stem and is locked in place by the cage 33' at the desired point. The two members are then pulled into their fully extended position with the shoulders 31 and 32 in tight pressure engagement, and a collet is placed around the upper portion of the stem 28 in pressure fitting engagement with the upper edge of the packing box bushing. After this has been done the valve member 37 is screwed up on to the bottom of the valve stem 36 until it is in tight pressure engagement with the seat or shoulder 39 and a locking member 45 is screwed on to the lower end of the valve stem below the valve 37. In this way the two shoulders 32 and 38 are adjusted so that they have the same space

relationship as the shoulders 31 and 39 on the outer or lower member. It will be observed that the lower member in this form of my invention is supported by the shoulders 31-32 and 38-39 and that such shoulders constitute positive pressure seals forming a chamber in the upper end of the lower member which communicates through the port or ports in the cage with the interior of the air chamber or upper member.

As has been previously pointed out it is one object of this invention to provide a bailer of the class described with an auxiliary by-pass valve between the air chamber and the sand chamber which will open in the event the pressure in the air chamber is in excess of the pressure in the sand chamber. This pressure relationship between the two chambers occurs when the unit has been withdrawn from the well full of sand with air under pressure in the top of the air chamber and after the sleeve valve 22 has been rotated to open the ports therein and establish atmospheric communication with the bottom of the sand chamber. In this form of my invention this auxiliary by-pass valve is shown as being formed in the valve member 37 by providing the lower end of the stem 36 with a chamber 50 having ports 51 in its upper end and provided with a seat 52 at its lower end. The seat 52 is adapted to be engaged by a check valve 53 which is shown as being yieldably held in pressure engagement with the seat by means of a coil spring 54 which is supported on a spider 56 threaded into a passage 57, which is formed through the locking member 45. With this arrangement it will be seen that irrespective of any relative movement between the two members 12 and 13, the valve 53 will open to establish communication between the air chamber and the sand chamber in the event the pressure in the air chamber is greater than the pressure in the sand chamber. This, as has been pointed out above, occurs when the valve 22 is opened after the bailer has been filled so that the upper end of the member 12 contains air under a substantial pressure.

Since it is not necessary nor desirable to have the enormous pressure encountered in the bottom of the hole within the air chamber when the unit is drawn to the surface of the ground, it is the practice to provide in bailers of this general character, a pressure release valve situated in the air chamber so as to relieve the pressure therein, as the bailer is withdrawn, until such pressure reaches a predetermined value. Such a pressure release valve is indicated by reference numeral 60 and may be of any desired type being capable of adjustment to retain within the air chamber the desired pressure for unloading the bailer.

It is to be understood that while I have herein described and illustrated one preferred form of my invention that the invention is not limited to the precise construction described above, but includes within its scope whatever changes fairly come within the spirit of the appended claims.

I claim as my invention:

1. In a bailer, the combination of: a lower tube member having an inwardly opening check valve in the bottom thereof; an upper tube member telescoping into the top of said lower tube; a downwardly facing shoulder in said lower tube forming a valve seat; a valve member secured to the bottom of said upper tube and adapted to be engaged by said seat, the bottom of said upper tube member above said valve being ported to provide communication between said upper

- and lower tubes when said valve member and said valve seat are out of engagement; and an automatic check valve in said upper tube adapted to establish communication between said upper and lower tubes when the pressure in the upper tube exceeds the pressure in the lower tube. 5
2. In a well bailer, the combination of: inner and outer telescoping members forming a sand chamber and an air chamber; spaced shoulders on one of said members; spaced sealing means on the other member adapted to engage said shoulders to form seals, one of said seals being located between the sand chamber and the air chamber, the other seal being located between the air chamber and the outer end portion of the passage in the outer member in which the inner member telescopes and a unidirectional check valve between said chambers adapted to open toward said sand chamber independently of any relative movement between said members. 10
3. In a bailer of the class described, the combination of: two telescoping tubular members, the inner member having a port at its inner end communicating with the interior of the outer member; means for limiting the collapsing movement of said members; means, comprising two sets of cooperating shoulders formed on said members both above and below said port and adapted to be engaged when said members are fully extended, for forming a sealed chamber in the outer member communicating with said port; and a unidirectional check valve positioned between said sealed chamber and the remainder of said outer member. 15
4. In a bailer, the combination of a lower tube member having an inwardly opening check valve in the bottom thereof; an upper tube member telescoping into the top of said lower tube; a downwardly facing shoulder in said lower tube forming a valve seat; a valve member secured to the bottom of said upper tube and adapted to be engaged by said seat, the bottom of said upper tube member above said valve member being ported to provide communication between said upper and lower tubes, said valve member being provided with a passage therethrough; and a 20
5. In a well bailer, the combination of: a pair of telescoping members adapted to be suspended in a well; valve means between said members adapted to be closed when said members are extended thereby forming an upper air chamber and a lower sand chamber; an inwardly opening check valve in the bottom of said sand chamber; a manually operable discharge valve at the bottom of said sand chamber; and a downwardly opening by-pass valve interposed between said sand chamber and said air chamber. 25
6. In a well bailer, the combination of: a pair of telescoping tubular members adapted to be suspended in extended relation with each other; valve means between said members adapted to be closed when said members are extended and opened when said members are collapsed thereby forming an air chamber in the upper member and a sand chamber in the lower member; an inwardly opening check valve in the bottom portion of said sand chamber; a discharge valve in the bottom portion of said sand chamber; and automatic by-pass valve means between said air chamber and said sand chamber adapted to open only when the pressure in the air chamber is greater than the pressure in the sand chamber. 30
7. In combination with a bailer having a sand chamber and an air chamber; valve means between said chambers adapted to be forcefully opened against an excessive pressure in said sand chamber; and an automatic check valve between said sand chamber and said air chamber adapted to open when the pressure in the air chamber exceeds the pressure in the sand chamber. 35
8. In a bailer, a suction chamber, a sand chamber, a valve controlling flow of fluid between said chambers, said valve being adapted to remain closed when the bailer is descending in the well and to open when the bailer encounters a major obstruction in the well, and a valve mounted between said chambers to permit flow of fluid from said suction chamber to said sand chamber when the bailer is removed from the well to assist in unloading said sand chamber. 40

WILLIAM J. FLURY. 45
